UNITED STATES PATENT OFFICE.

EMANUEL KERNS, OF SIBLEY, ILLINOIS.

SIDING-JACK.

SPECIFICATION forming part of Letters Patent No. 364,260, dated June 7, 1887.

Application filed February 4, 1887. Serial No. 226,573. (No model.)

To all whom it may concern:

Be it known that I, EMANUEL KERNS, a citizen of the United States, residing at Sibley, in the county of Ford and State of Illinois, have 5 invented a new and useful Improvement in Siding-Jacks, of which the following is a specification.

This invention is an improvement in flooring, ceiling, and siding jacks for carpenters' 10 use; and it consists in the peculiar construction and combination of devices, that will be more fully set forth hereinafter, and particularly pointed out in the claims.

In the drawings, Figure 1 is a perspective 15 view of a device embodying my improvements, illustrating the manner of using the same in laying flooring. Fig. 2 is a top plan view of my improved jack. Fig. 3 is a longitudinal sectional view of the same, taken on line xx of 20 Fig. 2. Fig. 4 is a detail perspective view of the shoe or head.

A B represents a pair of jaws, which are pivoted together upon a bolt or rivet, C. The jaws are arranged at such a distance apart as 25 to admit the insertion of an ordinary piece of studding or joist between them, and the said jaws are provided on their opposing sides, near their outer ends, with projecting studs D. The jaw A is provided with a handle, E, and 30 the jaw B is provided with a handle, F. The handle E is provided at its outer end and on its outer side with a curved loop or guard, G.

H represents a spring, which is secured to the arm E, near the inner end thereof, and 35 bears against the opposing side of the arm F, the function of the said spring being to normally diverge the said arms, so as to open the jaws A and B to their utmost extent.

I represents a shoe or head, which is provided on one side with a longitudinal groove, K, adapted to receive the usual tongues with 40 which flooring, ceiling, and drop-siding boards are commonly provided. This shoe or head I is centrally pivoted on the same bolt or rivet 45 C which is employed to pivot the jaws together, and thereby the shoe or head may be turned to any desired angle with respect to the arms and jaws.

The operation of my invention is as follows: 50 When the board to be forced home is laid

upon the studding, rafter, or joist, the operator grasps the handles of the jack with one hand and compresses them toward each other against the resilience of the spring and causes the clamping-jaws to force their studs or points 55 D into opposite sides of the stud, rafter, or joist, the shoe being so directed that the tongue of the board will enter the groove of the shoe. The studs or points D form fulcrums or pivotal points, upon which the jack is free to turn 60 when it is arranged in this position, as shown in Fig. 1, and the operator then forces the outer ends of the arms inwardly over the board, and thereby causes the shoe or head to bear against the tongued outer edge of the board 65 and force the same snugly into position against the adjacent board, which has been previously secured in place upon the joists, studs, or rafters. In this manner the tongued-and-grooved boards may be laid in position and secured to 70 form flooring, ceiling, or drop-siding very expeditiously.

Having thus described my invention, I claim—

1. In a jack, the combination of the handles 75 E F, having the jaws A B, provided with engaging studs D on their opposing sides, the bolt C, pivoting the jaws together, the head or shoe I, U-shaped in cross-section, pivoted on the projecting end of the said bolt, and the 80 spring adapted to normally distend the jaws, substantially as described.

2. A flooring-jack comprising the jaws A B, pivoted on a bolt, C, and a head or shoe, I, U-shaped in cross-section, pivoted also on the 85 same bolt, C, substantially as set forth.

3. A flooring-jack comprising the jaws A B, pivoted together, and a shoe, I, pivotally mounted on the pivot of said jaws, the jaws having handles E F, respectively, and the handle E being provided with a curved loop or guard, G, substantially as specified.

In testimony that I claim the foregoing as my own I have hereto affixed my signature in presence of two witnesses.

EMANUEL KERNS.
